UNITED STATES PATENT OFFICE

JACOB S. PREISNER, OF NEW HAVEN, CONNECTICUT

DESIGN FOR A FRET BAR FOR USE IN PLAYING STRINGED INSTRUMENTS

Application filed September 16, 1931. Serial No. 41,121. Term of patent 7 years.

To all whom it may concern:

Be it known that I, JACOB S. PREISNER, a citizen of the Union of Socialist Soviet Republics, residing at New Haven, in the county of New Haven and State of Connecticut, have invented a new, original, and ornamental Design for a Fret-Bar for Use in Playing Stringed Instruments, of which the following is a specification, reference being had to the accompanying drawing, forming part thereof.

Fig. 1 is a top view of a fret-bar for use in playing stringed instruments showing my new design;

Fig. 2 is a face view of the same;

Fig. 3 is an end view of the same; and

Fig. 4 is a perspective view of the same.

I claim:

The ornamental design for a fret-bar for use in playing stringed instruments as shown.

JACOB S. PREISNER.
